CENTRIFUGAL CASTING MACHINE

Frank G. Carrington, Anniston, Ala.

Application June 7, 1937, Serial No. 146,864

10 Claims. (Cl. 22—65)

The present invention relates to improved centrifugal casting equipment of the type having an exteriorly cooled mold rotatably mounted in a carriage which is telescopically movable with respect to an end pouring trough. Equipment of this type is widely used in the production of cast iron pipe and the like.

A principal object of the invention is the provision of centrifugal casting apparatus of the type described in which the rotatable mold is provided with a cooling jacket having improved intermediate mold-supporting means positioned to allow passage of cooling water about the mold and a centrifugally actuated cooling system for circulating water about the mold and supporting means sufficiently rapid to provide a relatively small difference in temperature at the ends of the mold.

An additional object is to provide a centrifugal casting device having a mold and an outer jacket carrying intermediate mold-supporting means which will allow for thermal expansion of the mold without permitting the mold to sag.

Another object of the invention is to provide improved mold-supporting means including spaced anchor members carrying therebetween spring bars provided with radial mold-supporting bars, the spring bars being tensioned to allow for thermal expansion of the mold without permitting the mold to sag.

Still another object of the invention is the provision of an improved cooling system for centrifugal casting machines.

A further object is to provide a cooling system for a centrifugal casting machine, in which water is circulated through a rotating mold-cooling chamber and non-rotating end jackets by centrifugal force and at a rate sufficient to provide a relatively low difference in temperature at the opposite ends of the mold.

These and other objects will be evident upon a consideration of the following specification and by reference to the accompanying drawings, in which

Fig. 1 is a longitudinal sectional view of a centrifugal casting machine constructed in accordance with my invention;

Fig. 2 is a bottom view of the machine shown in Fig. 1;

Fig. 3 is a view of the machine shown in Fig. 2 taken from the bell end thereof;

Fig. 4 is a sectional view taken along line 4—4 of Fig. 1;

Fig. 5 is a sectional view taken along line 5—5 of Fig. 1;

Fig. 6 is a sectional view taken along line 6—6 of Fig. 1; and

Fig. 7 is a sectional view taken along line 7—7 of Fig. 1.

In centrifugal casting machines for producing pipe, molten metal is poured from the end of an extended trough into a rotating mold which is progressively moved from telescopic relation with respect to the pouring trough. A mold of this type is indicated at 10 in the drawings.

At one end the mold 10 is of bell shape to form the enlarged overfitting end of the pipe to be cast, and an end core 11 is removably fitted into the bell end of the mold during the casting operation. After the pipe has been cast and withdrawn this core is removed in the usual manner.

The bell end of the mold has a flange 12 on its outside and the opposite end of the mold is provided with an enlarged cylindrical flange 13. The pouring spout (not shown) extends through flange 13 into the interior of the mold and the latter is reciprocally movable with respect to the pouring spout, as will be described.

To the flange 12 is fixed by means of screws one end of a mold jacket 14. This jacket extends the entire length of the mold and forms a compartment about the mold through which cooling water may be circulated. At its other end the jacket or casing 14 has a sliding but watertight fit with flange 13 of the mold. This sliding fit permits the mold to expand and contract longitudinally upon changes in temperature.

The mold is provided with intermediate supporting structure which prevents the mold from sagging while cooperating with the cooling system in permitting the circulating of water in free contact with the exterior of the mold. Two series of supporting members are shown in the drawings. As shown in Figs. 1 and 5, each of the

supporting structures consists of spaced screw-threaded anchor members 15. A steel spring bar 16 is secured to anchor members 15 by suitable nuts 17 and 18. Depending from the inner side of spring bar 16 is a radial mold-supporting standard 19 which passes through the mold jacket 14 and bears against the outer surface of the mold.

As shown in Fig. 5, there are a number of these mold-supporting units positioned about the mold in each of the two series of units, thereby affording support at relatively closely spaced sections about the circumference of the mold. As the mold-supporting standards are radially positioned and as the outer jacket 14 is of larger diameter than the mold, there are pro-

vided ample openings between the standards through which cooling water may circulate without overcoming an objectionable resistance.

The extended length of the mold and its weight creates a tendency for the mold to sag, particularly at high temperatures. The spring bars 16 have sufficient resiliency to allow for thermal expansion of the mold and at the same time are rigid enough to prevent the mold from sagging. That is, less force is required to prevent sagging than to prevent thermal expansion, and the force exerted by the spring bars is between these limits. By adjusting nuts 17 and 18 the tension exerted by bars 16 may be changed to the desired extent.

When the mold turns at a high rate of revolution there is a tendency for the machine to vibrate unless the mold is supported properly, the vibration being caused by a loss of dynamic balancing. The turbulence caused when the inflowing stream of molten metal strikes a vibrating mold often will produce defects in the casting. In the case of slender molds such as those used for casting pipe 6 inches in diameter and 18 feet long the effort exerted by the intermediate supporting units in preventing the sagging and warping of the mold may be of the order of 10 per cent of the effort required to prevent thermal expansion.

The casting mechanism is provided with a cooling system in which water is circulated through the outer jacket 14 in a direction toward the bell end of the mold. A baffle 20 at the bell end of the jacket insures passage of the water to the end of the mold. After passing around the baffle 20 the water reverses its direction and then passes outwardly through orifices 21, which are located at spaced intervals about the cylindrical bearing surface 22 at the bell end casing 14.

Surrounding the bearing surface 22 at the bell end of the machine is a non-rotating circular end casing or shell 23 which is sealed with respect to the surface 22 by means of packing 24 and rings 25. The casing 23 forms a collection chamber for cooling water passing from the bell or outlet end of the cooling chamber formed by jacket 14.

At its bottom the casing 23 communicates with a return water jacket 24 which extends longitudinally of the machine and terminates adjacent the other end of the mold. The terminal end of return jacket 24 communicates with a non-rotating circular end shell or casing 25. Casing 25 surrounds the end of the mold jacket 14 and the latter is mounted to rotate within this casing by means of packing 26 and rings 27. Thus, casing 25 forms a bearing for the rotatable mold jacket which will prevent loss of cooling water. Casing 25 also constitutes a supply chamber from which cooling water enters jacket 14 through a series of openings 28 located at spaced intervals in the jacket.

It will be noted from Fig. 1 and from a comparison of Figs. 4 and 7 that the outlet casing 23 is larger in diameter than inlet casing 25. When the mold and jacket are rotating, the amount of centrifugal force set up in the water of the cooling system will depend upon the distance of the water from the center of rotation. As the water at the bell end of the jacket 14 is farther from the center of rotation than at any other point, the rotation of the mold causes a flow of water from jacket 14 into the outlet casing 23. The water then flows from the outlet

casing through return jacket 24, inlet casing 25, and back into the jacket 14 by way of openings 28. To prevent backflow, the return jacket 24 is provided with a check valve 29, as shown in Fig. 1.

In traversing the jacket 14 the water comes in intimate contact with the mold and maintains the latter at the desired temperature. The temperature of the water entering the jacket 14 from inlet casing 25 is lower than the temperature of the water leaving the cooling jacket at the bell end of the machine. This temperature gradient results in different cooling conditions at the two ends of the mold. The rapid circulation obtained by my cooling system maintains a relatively low temperature gradient and as a consequence a desirable uniformity of results is obtained.

The rate of circulation of water depends upon the difference in radial distances from the center of rotation of the water at the inlet and outlet ends of the cooling jacket and upon the rate of rotation of the mold. These factors co-operate to produce a rapid rate of circulation.

The circulation system described is provided with a fresh water inlet line 31 which extends between the chamber provided by casing 24 and temperature regulation valve 32. Valve 32 also communicates with a longitudinally extending supply line 33, which connects through a gland 34 with a telescoping section 35. On the opposite side of the casing 24 an outlet line 36 communicates through valve 37 with a discharge line 38. This discharge line connects through a gland 39 with a telescoping section 40. The supply and discharge lines for the cooling water travel with the carriage as the latter reciprocates away from and toward the pouring spout.

The pressure on the inlet side of the fresh water supply line 31 is sufficiently greater than the pressure inside the circulation system to permit the addition of the desirable amount of fresh water to the water recirculating about the mold. An admixture of the fresh water with the water which is returned from the shell 23 is had in the casing 24 and it is this mixture of water which passes about the mold from the casing 25. The outlet valve allows escape of hot water from the opposite side of the casing 24 and this water passes to waste through lines 36 and 40.

The reciprocation of the mold carriage is produced by engagement of a flange 41 on the bell end of the casing 24 with a piston rod 42 which is actuated backwardly and forwardly by an hydraulic cylinder (not shown). In moving toward and away from the pouring spout, the carriage 30 travels on wheels 43 which are secured to the carriage on suitable axles. The wheels 43 roll along track portions 44 of the base member 45. Thus, the entire machine moves longitudinally of the axis of the mold toward and away from the pouring spout along the supporting track, the water inlet and outlet pipes 33 and 38 telescoping respectively into and out of the pipes 35 and 40.

During the pouring operation the mold and mold casing are rotated at the desirable rapid rate by the drive gear 46. Gear 46 surrounds the jacket 14 at the approximate center thereof and is driven by a suitable motor (not shown) mounted on the carriage. The gear 46 likewise is connected with an outstanding flange ring 47 which rotates in the slot 48 of a block 49 which is rigidly secured to the carriage 30, as shown in Fig. 1. This block prevents longitudinal move-

ment of the mold during withdrawal of pipe therefrom.

The mold jacket is supported on a number of rollers 50, as shown in Fig. 6, these rollers being mounted on opposite sides of the mold center and supported on stanchions 51 positioned on the bottom of the mold carriage.

In operation of the machine the mold carriage is moved into telescopic relation with respect to the pouring spout and the mold is set into a state of rapid rotation. The molten metal first is poured into the bell end of the mold and the carriage then is moved away from the pouring spout at a very uniform rate by the hydraulic piston rod 42. The rapid rotation of the mold sets up a centrifugal pressure in the bell end of the circulating system which causes water to pass from the shell 23 through the casing 24 and into the inlet shell 25. From the inlet shell the water circulates through openings 28 in the mold jacket and passes in contact with the mold throughout its length back to the casing 23. The valve 32 permits the entrance of the desired amount of cooling water into the casing 24 where it mingles with the circulated water bypassed about the mold. The check valve 29 is raised by the flow of water. When the rotation of the mold is stopped the check valve 29 permits a continuance of the flow of water from the inlet 30 to the outlet lines, the inlet being on the downstream side of the check valve.

The casting cycle for the commercial sizes of 4 inch, 6 inch, and 8 inch diameter pipe, 18 feet long, is of the order of one to two minutes. As soon as the metal has solidified and cooled sufficiently to allow it to be handled the casting is withdrawn and the mold is prepared for the next casting. The structure and qualities of the casting are affected by the temperature of the mold, it being desirable that the mold be brought back to the same temperature at the beginning of each pouring operation. Practically all the heat removed from the mold passes into the water of the cooling system. This transfer of heat from the mold is dependent upon such factors as the temperature difference between the mold and the water and the velocity at which the water passes over the mold surface. By properly adjusting the diameters of the two end casings of the machine and the use of a by-pass flow, the centrifugal pressure developed during the casting operation by the rotating mold provides for a rapid circulation of water and optimum cooling conditions. The by-pass chamber provided by casing 24 is large enough to act as a reservoir for circulated water and prevents the incoming fresh water from having a sudden chilling effect on the mold.

Various changes may be made in the details of construction described herein without departing from the scope of the invention as defined in the appended claims.

I claim:

1. In a centrifugal casting machine of the type telescopically movable with respect to an end pouring trough, the combination of an externally cooled mold, a cooling jacket surrounding said mold and being spaced therefrom to form a water compartment, a series of intermediate supporting units between said jacket and said mold, said units including spaced radial mold supports extending through said water compartment and jacket, and spring bars bearing against said supports with a pressure sufficient to resist sagging but insufficient to resist thermal expansion of

said mold, and means for recirculating water through said water compartment and between said mold supports.

2. A centrifugal casting machine, comprising a metallic mold, a cooling jacket surrounding said mold and being spaced therefrom except at its ends, and a series of intermediate mold-supporting units between said jacket and mold, said units including mold-supporting members having their inner ends bearing against said mold and extending outwardly therefrom, and spring bars supported by said jacket for engagement with the outer ends of said supporting members with sufficient pressure to resist sagging of said mold but insufficient to resist thermal expansion thereof.

3. A centrifugal casting machine, comprising a metallic mold, a cooling jacket surrounding said mold and being spaced therefrom to form a water compartment, and intermediate mold-supporting units between said jacket and mold, each of said units including a mold-supporting member having its inner end bearing against said mold and extending radially therefrom through said jacket, spring bar securing means on opposite sides of said supporting member and a spring bar secured by said means and bearing against said supporting member with a pressure sufficient to resist sagging of said mold but insufficient to prevent thermal expansion thereof.

4. A centrifugal casting machine of the type telescopically movable with respect to an end pouring trough, comprising an externally cooled metallic mold, a cooling jacket surrounding said mold and being spaced therefrom for substantially the full length of the mold, one end of said mold being longitudinally expansible with respect to said jacket and the other end of said mold being rigidly attached to said jacket, means for rotating said mold and jacket as a unit, a non-rotating casing adjacent each end of said jacket, said jacket having openings communicating with said casings, and one of said casings having a greater diameter than the other of said casings to provide a centrifugal pressure differential therebetween, a return conduit between said casings, and inlet and outlet conduits communicating with said return conduit.

5. A centrifugal casting machine of the type telescopically movable with respect to an end pouring trough, comprising an externally cooled rotatable metallic mold having an enlarged bell end, a cooling jacket surrounding said mold for substantially its entire length and forming a water compartment, a non-rotating casing surrounding said jacket adjacent each end thereof, said jacket having spaced openings communicating with said casings and the casing adjacent the bell end of the mold being of larger diameter than the other of said casings to establish a centrifugal pressure differential therebetween upon rotation of said mold, and a return conduit connecting said casings.

6. A centrifugal casting machine of the type telescopically movable with respect to an end pouring trough, comprising an externally cooled rotatable metallic mold, a cooling jacket surrounding said mold and forming a one way conduit for cooling water, a non-rotating collection casing communicating with said conduit adjacent one end of said jacket and a non-rotating supply casing communicating with said conduit adjacent the other end of said jacket, a return conduit connecting said casings, and means for recirculating cooling water through said one way conduit.

said collection chamber, said return conduit and said supply conduit.

7. A centrifugal casting machine of the type telescopically movable with respect to an end pouring trough, comprising an externally cooled rotatable metallic mold, a cooling jacket surrounding said mold and forming a one way conduit for cooling water, a non-rotating collection casing communicating with said conduit adjacent one end of said jacket, a non-rotating supply casing communicating with said conduit adjacent the other end of said jacket, a return conduit connecting said casings, a check valve in said return conduit, an inlet conduit communicating with said return conduit on the downstream side of said check valve and an outlet conduit communicating with said return conduit on the upstream side of said check valve.

8. A centrifugal casting machine of the type telescopically movable with respect to an end pouring trough, comprising an externally cooled rotatable metallic mold having an enlarged bell end, a cooling jacket surrounding said mold and forming a one way conduit for cooling water, a relatively large non-rotating casing surrounding said jacket adjacent the bell end of said mold and communicating with said one way conduit, a relatively small non-rotating casing surrounding said jacket adjacent the other end of said mold and communicating with said one way conduit, a return conduit between said casings a check valve in said return conduit a cool water supply line communicating with said return conduit on the downstream side of said check valve, and an outlet conduit communicating with said return conduit on the upstream side of said check valve.

9. A centrifugal casting machine of the type

telescopically movable with respect to an end pouring trough, comprising a longitudinally extending rotatable jacket having an enlarged bell end and spaced openings adjacent each end, a metallic mold carried in said jacket, said mold having an enlarged bell end fixed to the bell end of said jacket and being slidably mounted at its other end in said jacket, intermediate spring-pressed mold supports carried by said jacket and bearing against said mold, said supports being spaced apart sufficiently to permit free flow of cooling water between said jacket and said mold, non-rotating casings enclosing said jacket about the openings adjacent each end, a return conduit between said casings, a check valve in said conduit, a telescoping cool water supply line communicating with the return conduit on the downstream side of said check valve, a telescoping outlet line communicating with the return conduit on the upstream side of the check valve, and means for reciprocating the aforesaid elements longitudinally of the axis of the mold.

10. A centrifugal casting machine of the type telescopically movable with respect to an end pouring trough, comprising a metallic externally cooled mold, a cooling jacket mounted about said mold in spaced relation thereto, said jacket being fixed to said mold at one end and supporting said mold at its other end in slidable relation, central drive means for rotating said jacket, and spring-pressed mold supports carried by said jacket on opposite sides of said drive means and bearing against the exterior of said molds with a pressure sufficient to resist sagging but insufficient to resist radial thermal expansion.

FRANK G. CARRINGTON.
